Primary Examiner — Paula Allen Greene(74) *Attorney, Agent, or Firm* — TraskBritt(57) **CLAIM**

The ornamental design for a headphone, as shown and described.

DESCRIPTION

FIG. 1 is a perspective view of an embodiment of a headphone;

FIG. 2 is a front side view of the headphone shown in FIG. 1;

FIG. 3 is a back side view of the headphone shown in FIG. 1;

FIG. 4 is a right view of the headphone shown in FIG. 1;

FIG. 5 is a left view of the headphone shown in FIG. 1;

FIG. 6 is a top view of the headphone shown in FIG. 1; and,

FIG. 7 is a bottom view of the headphone shown in FIG. 1.

The broken lines in FIGS. 1 through 7 are for environmental

purposes only and do not form any part of the claimed

design.

The ornamental design for a headphone, as shown and described.

1 Claim, 6 Drawing Sheets
